INVENTOR

John J. Heys
By His Attorney,
Nelson McDonald

UNITED STATES PATENT OFFICE.

JOHN J. HEYS, OF LYNN, MASSACHUSETTS, ASSIGNOR TO UNITED SHOE MACHINERY CORPORATION, OF PATERSON, NEW JERSEY, A CORPORATION OF NEW JERSEY.

LAST.

1,312,543.

Specification of Letters Patent.

Patented Aug. 12, 1919.

Application filed March 18, 1918. Serial No. 228,114.

To all whom it may concern:

Be it known that I, JOHN J. HEYS, a citizen of the United States, residing at Lynn, in the county of Essex and State of Massachusetts, have invented certain Improvements in Lasts, of which the following description, in connection with the accompanying drawings, is a specification, like reference characters on the drawings indicating like parts in the several figures.

This invention relates to lasts, and in particular to separable lasts whose heel parts are separable from the foreparts and removable while the last is in the shoe. Lasts of this type have been proposed for use in shoemaking according to that process wherein the heelng operation is performed on a jack after the removal of the last heel part leaving the forepart of the last in the shoe. The removal of the last heel part permits the attachment of the heel by either outside or inside nailing, and without any danger of crushing the heel part in the former operation, while the forepart of the last holds the forepart of the shoe in position under lasting tension. The heel part and general construction of such a last need not be as strong and expensive as in lasts on which heelng is done, and, further, the heel part when removed can be at once used with another forepart in making another shoe, while the first-mentioned shoe is setting on its last fore-part; and thus one heel part can be made to do for several foreparts, and the amount of invested capital per pair of shoes manufactured can be decreased.

Difficulty has been experienced in providing a last which shall shorten rapidly and to a sufficient extent to permit ready removal of the heel part without disturbing the forepart, and which shall at the same time be markedly cheaper than lasts on which heelng is done. My invention is directed to the overcoming of this difficulty.

It has been found to be desirable to give a swinging movement to the heel part of a collapsible last in shortening it; as distinguished from a movement of translation only. When the heel part is thus swung on a hinge pin, as has been frequently proposed, the pin has to be located well up in the body of the last, in order to secure the requisite strength, and this causes the last to lengthen slightly before it shortens, or to shorten so slowly that the broad tread portions of the

heel cannot slip readily through the counter portion of the shoe; whereas it is desirable that it shorten at once, and rapidly. Lasts of this type which have dispensed with the hinge pin have used more or less complicated bonding hinge mechanisms, which weakened the last owing to the extensive cutting required to insert them, and are expensive.

In accordance with important features of the invention my last is divided by a circular arc swung about a center lying below the heel bottom and has a shoulder to hold the heel part against movement backward from extended position, and is provided with a separable bonding means permitting the disengagement of the heel part from the forepart as the heel part slides on the circular cut.

These and other features of the invention, including certain various arrangements and combinations of parts, will be best understood from the following description of a preferred embodiment of the invention, selected for purposes of illustration and shown in the drawings in which,

Figure 1 is a broken-away elevation of the last;

Fig. 2 is a similar view showing the last in its initial collapsing movement;

Fig. 3 shows the last parts separated.

The last is divided by two circular cuts 10, 12 taken about a center 14 lying, in the last shown, substantially in the tread face of the ball portion. It will be apparent as the description proceeds that this center can be placed as desired, since it physically plays no part in the collapsing of the last. The two cuts 10, 12 are joined by a short horizontal cut 16, the heel part portion thereof overhanging the forepart portion.

The bonding means comprises a pin 18 and a hook 20, mounted in the forepart and heel part, respectively, in the last shown. The hook is anchored in a slot in the heel part by rivets 22, and extends into a slot in the forepart, across which the pin 18 extends. The slot 24 of the hook is arcuate, having the same center 14 as the cuts 10, 12, when the last is assembled.

The last is locked against collapsing by a spring-held pin 26 mounted in the forepart and projecting into a bushed hole 28 in the heel part. In collapsing the last, a tool 30 may be used to depress the pin 26 and then to pull the heel part forward. The

curves 10, 12 lie entirely above the center 14, and consequently the curve 10 terminates in a portion extending in a horizontal direction through the instep, instead of a 5 nearly vertical portion through the cone, so that a pronounced forward movement of the heel part takes place in the collapsing operation. The heel part will slide freely and easily forward about the center 14, the last 10 shortening from the very beginning of the movement, since the center 14 lies below the heel bottom. When the hook has risen sufficiently to become disengaged from the pin 18 it disconnects the two last parts and the heel 15 part may be lifted out of the shoe, leaving the forepart undisturbed. There is no complicated bonding mechanism to stick and cause the displacement of the forepart in the shoe. The fittings used in the last 20 shown are exceedingly cheap and simple. The three pins are cut from bar steel and the hook member 20 is a punching.

The shape of the surface 16 locks the heel part positively against backward movement, and also supplies a firm bearing 25 against twisting stresses.

Having thus described my invention, what I claim as new and desire to secure by Letters Patent of the United States is:-

1. A separable last divided on a circular 30 arc swung about a center lying below the heel bottom and having a shoulder to hold the heel part against backward movement from extended position, the forepart having a recess with a pin therein, a hook in the 35 heel part extending beneath said shoulder and into the recess in the forepart for engaging said pin, and a locking pin in one last part engaging the other part to lock said parts against collapsing movement. 40

2. A separable last divided by two circular arcs swung about a center lying below the heel bottom and joined by a substantially horizontal cut, the heel part side thereof overhanging the forepart side, and 45 having a pin and hook bonding means constructed and arranged to slide into engagement and disengagement as the heel part slides on the circular dividing cut.

In testimony whereof I have signed my 50 name to this specification.

JOHN J. HEYS.
